CONVEYER FOR CHOCOLATE PRODUCTS

Fritz Nestmann, Dresden, Germany, assignor to
the firm of J. M. Lehmann, Dresden, GermanyApplication May 31, 1938, Serial No. 210,999
In Germany June 4, 1937

9 Claims. (Cl. 198—85)

This invention relates to a cooling, heating and drying device, particularly for chocolate products.

Cooling of chocolate articles disposed in firm molds is effected by devices having vertical conveyers which insure thorough cooling and require little space.

Coated articles on the other hand that are to be cooled and dried do not come out of the machine disposed in firm molds but are individually arranged on a band conveyer from which they are taken off, usually by means of an additional band conveyer closely adjacent the first one.

In the known devices, the articles taken off in the manner indicated are then guided through cooling or drying tunnels of corresponding length, which are arranged around the band conveyer. As the tunnel must be quite long to insure effective cooling, these known devices require a lot of space.

The invention solves the problem by causing a horizontal band conveyer fitted with sheet drivers to pass smoothly through a chamber whilst the supports held by the carrying members of the conveyers can carry out a closed cycle. For this reason, the two conveyers are subdivided where the horizontal band conveyer is positioned, the main upper portion serving for passing the articles through the chamber whilst the portion lying below the band and provided with special conveying means is used for bringing the supports released by the upper portion into the plane of the transverse band conveyer, transversely moving them under the conveyer band after removal of the articles, raising them again up to the level of the plane of the band for the reception of fresh articles and transmitting them to the conveyer that is moving up.

If only one support carrier is to be released or engaged in this manner, the vertical conveyers must have intermittent motion, so that during upward motion of one conveyer the other one must remain stationary and during downward motion of one conveyer the other one must remain stationary also. For accelerated operation and simultaneous intermittent motion of both conveyers it is only necessary to simultaneously raise or lower two superposed support carriers.

By way of example, the invention is illustrated in the accompanying drawings in which two embodiments of the invention are shown and Figure 1 is a diagrammatic view showing the circular course of the hurdles within the refrigerator and the supply and discharge of the sheets; Fig. 2, a view of a device embodying the features re-

ferred to in Fig. 1; Fig. 2a is the right end portion of Fig. 2; Fig. 3, a partial view of the conveying means supplying the sheets to, and delivering them from, the refrigerator; Fig. 4 shows the passage of the hurdles from the conveyer portion disposed above the horizontal band conveyer to the lower conveyer portion; Figs. 5 to 7 illustrate also the passage of the hurdles through the horizontal conveying means and the special construction of the vertical conveying means for the hurdles; Fig. 8 shows a modification in which the vertical conveyers alternately move up and down; and Fig. 9 diagrammatically shows the guiding of the sheets at the points of reversal of the conveyer 3.

Within the refrigerator hurdles serve as carriers for the sheets of paper which support the articles to be cooled. Each hurdle has a charging area generally corresponding to the size of the sheet to be placed on the hurdle.

The hurdles 1, shown in Fig. 2, carry out the cycle indicated by arrows within the cooling cupboard 2. No difficulties would arise if it were only necessary to pass through this cycle, but the trouble is that the cycle of the hurdles 1 is crossed by the horizontal conveyer 3 which effects the circular motion of the sheets of paper 4. For this purpose, the horizontal conveyer 3 comprises parallel chains spaced so as to permit the hurdles 1 to be guided through between both chains which possess stops 5 oppositely arranged relative to one another and abutting against cross bars 6 to which the sheets 4 are secured. In this manner the sheets 4 are driven at the motion of the chain 3.

In the coating machine 7 the articles to be coated with chocolate rest on a band conveyer 106 of the lattice or sieve type to facilitate the removal of excess chocolate fed during the coating operation. The band conveyer 106 of the coating machine 7 and the conveyer 3 of the cooling device rotate in the same direction, both conveying means lying in the same plane and their strands running on and off are guided in acute-angled fashion so as to insure the passage of the articles from one conveying means to the other. In support of the chains 3 angular supporting faces are provided, as indicated in Fig. 9. As long as the sheets 4 rest with their bars 6 on these angular supporting faces they are safely guided. When however the conveyer 3 is guided out of its horizontal and into downward direction, it is necessary to provide for the bars 6 a bearing surface which in combination with the stops 5 insures safe guiding of the bars 6 and thereby

proper conveyance of the sheets 4. Only in this manner can the sheets 4 rotate in an orderly way and during rotation pass within range of the band conveyer of the coating machine 7, which charges them with the articles to be cooled. The sheets are then brought into the cooling device and pass out of it over the table 9 when cooling is completed. At a change in conveying direction a conveying means 37 is brought again so close to the conveyer 3 that the articles can pass from the sheets 4 to the conveyer 37.

If the sheets 4 are to be properly transmitted to the hurdles 1 the intermittent vertical motion thereof must occur in such manner that an ascending and a descending hurdle 1 always stops at the same level, i. e. of the feed table 8 and the delivery table 9. When the hurdles are in this position of alignment with the tables 8 and 9, a sheet 4 is introduced into the hurdle next to the table 8 and delivered from the hurdle closest to the table 9.

This feeding method is possible only if the hurdles 1 are not directly superposed but are spaced so as to permit the horizontal conveying means to act. For sheet delivery the hurdles 1 possess clearances 36 to pile up the hurdles when sheets are drawn off. The hurdle 1 nearest to the table 8, after receipt of the sheet, is conveyed upwardly by the vertical conveying means.

The hurdle 1 closest to the table 9, from which the sheet has been removed, is, however, moved downwardly. As mentioned before, the conveyer moving transversely to the vertical conveyers requires a special construction of the latter, since the hurdles moved by the vertical conveyers describe a closed cycle.

Fig. 4 shows how the passage of the hurdles 1 through the horizontal conveying means is effected. The direction of the arrows indicates that in the example shown the hurdles are moving down carried by angles 10 which are secured to the transfer chains 11 in known manner. These transfer means terminate, however, above the horizontal chains 3 and guide the hurdles only within range of the chains 3 and transmit them to conveying means which receive them and pass them between the chains 3.

The lowermost hurdle engaged from below by the slide 14 is placed by the latter upon rolls 38 on which it is displaced to the left by the nose 17 of the conveying chain 18 which passes over the sprocket wheels 19 and 20 and is thus brought within range of an ascending slide 21 which can be displaced along the guides 22, 23. Fig. 2 shows how the slides 14 and 21 are brought into connection with one another by a cross rod 24. They form a sort of balance on which the hurdles located above the slide 14 are moved down and those positioned above the slide 21 are moved up.

There are also levers 12 provided for the upward motion of the hurdles 1 for engaging the hurdles brought up by the slide from below and holding them on a level with the conveyer chain 3 to introduce the sheet 4. After the sheet has been put on, the slide 21 is moved up still farther until the hurdle is brought within range of the angles or drivers 10 of the conveying chain 11. This chain drives the hurdles in known manner, which, as indicated in Fig. 2, pass within range of drivers 25 secured to the conveying chain 29. The conveying chain 29 passes over the sprocket wheels 27, 28 effecting motion of the chain 29 in the direction of the arrow and passing the uppermost hurdle of the left-hand

conveyer to the right-hand conveyer which moves it down. During the transverse displacement the conveyers must be stopped.

It is further possible to construct the vertical conveyers shown in Fig. 4 and representing chains provided with angles in a different manner.

In this instance, as indicated in Figs. 5 to 8, the hurdles 1 possess obliquely bent edges 29 to facilitate accurate piling of the hurdles. It is possible to arrange quite a number of hurdles, one above the other, in this way. Instead of the chains used for moving the hurdles up and down pistons 31, 32 are provided which during descent move past the bent up edges 29 of the hurdles 1 and engage them from below. During the ascent they guide the hurdles engaged by them upwardly and thereby the entire set of hurdles arranged on the engaged hurdle. Since at each side of a hurdle two pistons 31, 32 are provided, they can operate alternately, one holding the hurdle in a certain position and the other one moving down in the meantime and engages the next hurdles from below.

Figs. 5 to 7 show the various positions which occur while the hurdles are moving up and through the conveying chain 3. Fig. 5 shows the lowermost hurdle disposed on a conveying rail 33. The next hurdle is engaged from below by the piston 32 and the next one by the piston 31. The piston 31 goes up and guides the hurdle with which it is associated as well as the hurdles superposed thereon in upward direction. The superposed set of hurdles has thus been separated, and the transverse conveying means cooperating with the chain 3 can now begin to operate and place a sheet 4 on the hurdle exposed within range of the chain 3. During the ascent of the piston 31 the piston 32 has moved down and engaged from below the lowermost hurdle disposed on the rail 33, as shown in Fig. 6. Fig. 7 shows how thereupon during the ascent of the piston 32 the lowermost hurdle is brought again on a level with the conveying chain 3 and simultaneously connection with the superposed hurdles is established, so that the piston 31 can release them and, as indicated in Fig. 5, engage again a lower hurdle. This cycle is then repeated again including the feeding of the lowermost hurdle on the rail 33. In the same manner as the hurdles are lifted, lowering thereof is effected by means of the adjacent conveyer. Transverse motion of the hurdles on top and below can be similarly effected by means of the conveyer chains 18 and 28, as indicated in Figs. 2 and 4.

The device is driven as follows:

In the bearing brackets 40, 41 the driving shaft 42 is rotatably arranged and only partly shown in the drawings for the sake of clearness. The end of the shaft 42 facing the bracket 41 supports a worm 43 which is in mesh with a worm gear 44 firmly arranged on a shaft 45 rotatably disposed in the machine frame. Firmly connected with the shaft 45 is a sprocket 46 from which by means of the chain 47 a sprocket 48 on a shaft 49 is driven which is also rotatable in the machine frame and has secured thereto a toothed wheel 50 meshing with a toothed wheel 51 on a shaft 52. The shaft 52 supports, furthermore, the sprocket wheel 34 over which the chain 3 passes. By means of the sprocket wheel 34 drive of the chain 3 is effected, the other sprockets connected with the chain 3 merely serve for guiding purposes.

The shaft 52 further supports a sprocket wheel

53 which with the aid of the chain 54 drives the sprocket 55 on the shaft 56 supporting also a roller 57 over which the conveying band 37 runs which is therefore driven by the roller 57.

The shaft 49 is provided with a sprocket 58 which drives the sprocket 60 on the shaft 61 by means of the chain 59. The shaft 61 supports a sprocket wheel 62 from which the sprocket 64 on the shaft 65 is driven by means of the chain 63. The shaft 65 is further provided with a disc 66 which cooperates with a Maltese cross 67 arranged on the shaft 68. The disc 66 is for this purpose provided in known manner with a driving pin 69 which engages the clearances 70 of the Maltese cross 67 and thereby effects intermittent rotation of the cross. The shaft 68 is provided with a sprocket wheel 71 which engages a sprocket wheel 73 on a shaft 74 by means of the chain 72. The shaft 74 supports a bevel gear 75 in mesh with the bevel gears 76, 77 and driving them and their shafts. As the shafts move in opposite directions, the conveyers will also be started oppositely and intermittently owing to the intermittent drive by means of the Maltese cross 67.

Since the sprocket wheel 20 is firmly arranged on the shaft 61, it will cooperate in the rotation thereof and transmits its motion to the sprocket wheel 19 by means of the chain 18 while the stops 17 carry along the hurdles 1 located on the rolls 38. To limit the stroke of the stops 17 the latter are movably disposed on the conveying chain 18 at 78, though they are guided with their lower face 79 along the paths 80 and kept in upright position, Fig. 2, as long as they are passing over the guide 80. When the stops 17 reach the end 81 of the path 80, they can turn about their shaft 78, so that when they leave the path 80 the displacement of the hurdles 1 is completed also.

The stops 17 have, however, still another function to fulfil. They engage behind the stops 82 disposed on the chain 83 and keep on moving this chain until engagement between the stops 17 and 82 ceases. For limiting this engagement another guide rail 84 is provided which maintains the stops 17 in vertical position. As long as the stops 17 slide along the guide path 84, they find enough support and cannot rotate. This support ceases, however, when the stops 17 leave the path 84, so that rotation of the stops becomes possible and they cannot transmit power any more with the result that the motion of the chain 83 is finished. The chain 83 supports several equidistantly spaced stops 82 distributed in such manner that after a stop 17 has left the guide path 84 a fresh stop 82 is placed in the way of the next stop 17 to insure intermittent motion of the chain 83 which passes over the sprockets 85, 86 on the shafts 87, 88. On the shaft 88 a disc 89 is firmly disposed which with a pin 90 engages a slot 91 of longitudinal configuration in the widening portion 92 of the lever 24 capable of rotating about the shaft 88.

During motion of the chain 83 the disc 89 with its pin 90 is rotated also and, owing to the engagement of the slot 91 by the pin 90, the lever 24 alternately moves to and fro about its shaft 88. The lever 24 possesses oblong holes 94, 95 which cooperate with pins 96, 97 firmly arranged on the guide rods 88, 89, so that at a motion of the lever 24 about its shaft 88 the guide-rods 88, 89 will be alternately lifted and lowered in their guides 22, 23 and 15, 16. On the guide rods 75

98, 99 the slides 14, 21 are provided for effecting vertical displacement of the hurdles.

The sprocket 19 is firmly arranged on the shaft 100 supporting an additional sprocket wheel 101 over which the chain 102 runs which drives the sprocket wheel 103 on the shaft 104. The shaft 104 supports also the sprocket wheel 27 which drives the chain 29 passing over the sprocket 28 and the stops 25 which displace the hurdles 1 in the direction of the arrow. For limiting the path along which the stops 25 are effective, guide paths 105 are provided in a similar manner as described above.

The drive of the conveyer 106 of the coating machine 1 is brought about by the worm gear 107 arranged on the shaft 42 within range of the bearing bracket 40. The worm gear 107 is in mesh with a worm gear 108 on the shaft 109 which supports a sprocket wheel 110 which drives the sprocket wheel 112 on the shaft 113 by means of the chain 111. On the shaft 113 the driving roller 114 for the conveyer 106 is disposed.

It should be noted that, though only one chain and sprocket wheel have been mentioned above, the chains 3, 83 are provided in pairs like the sprockets over which these chains are guided.

The hurdles coming from above must be held at a level with the chains 3 to enable the stops 5 thereof to withdraw the sheets 4. For holding the hurdles at this level levers 12 are provided which oscillate on the shaft 13 and are drawn by springs 115 against stationary stops 116. After withdrawal of the sheets the hurdles must be moved farther down, which necessitates rotation of the levers 12 about their shaft 13 by means of the rods 117 rotatably articulated at 118 to the other end 119 of the levers 12. These rods 117 are vertically suspended by their own weight which, however, cannot be converted into a motion of the levers 12, because the force of the spring 115 which holds the lever to the stop 116 is greater. When during ascent of the member 92, part 120 strikes against the stop 121 on the rod 117, the latter will be forced up and the lever 12 laterally swung out, so that the hurdle previously supported thereby can move down. The gear members arranged on the other side of the device are constructed symmetrically.

When the levers 12 are moved toward the hurdles they engage such hurdles from below and hold them exactly in the plane of the tables 8 and 9 so that the chains 3 may feed the sheets 4 to the hurdles or remove them therefrom. The angle irons 10 release one hurdle at a time and place it directly upon the hurdle underneath. The two superposed hurdles are then displaced by a slide 14 capable of vertical downward movement along the guides 15 and 16.

Before the levers 12 are released, the slide 14 has gone up and directly engaged under the hurdle held by the levers 12. During release of the levers 12 the hurdle is therefore supported by the slide 14 which then moves down and places the hurdle on the rolls 38 whilst the levers 12 immediately pass into a position of readiness and engage the next hurdle from below. The levers 12 are arranged on each side in pairs.

They are provided also for the ascending conveyer where the hurdles coming from below control the swinging motion, so that the linkages 118 to 121 for effecting the swinging out of the levers 12 are omitted.

In the construction shown in Figs. 5 to 7 the hurdles are lifted by means of pistons 31, 32

guided in guides 122 and provided at their lower ends with rolls 123, 124 which cooperate with the eccentrics 127, 128 firmly disposed on the shafts 125, 126. When the eccentrics 127, 128 are rotated, the pistons 31, 32 are moved up and down. The eccentrics 127, 128 are staggered relative to each other and the arrangement is such that one of the eccentrics does not cause any motion of the associated piston while the other piston is being moved. The pistons 31, 32 carry at their upper end the cross levers 129, 130 which at 131, 132 are articulated thereto. They can freely turn upwardly about their joints, but their downward motion is limited by the stops 133, 134. When the piston 32 moves up, the cross lever 130 is placed on the top 134 which engages therefore the hurdles at their edges 29 and guides them upwardly. On the other hand, when the piston 32 goes down, the cross lever 130 can swing about its joint 132, which causes no motion of the hurdles 1 but brings the cross lever out of reach of the edge 29.

The hurdles can be moved up or down by corresponding operation of the pistons 31, 32.

The device substantially functions as follows:

After the sheets 4 have been charged by the conveyer of the coating machine 7 with the material to be cooled, they pass over the table 8 to the hurdles 1. The sheets travel with the hurdles through the cooling device, first upwards, then sideways and downwards until they are again within range of the chain 3 which with its stops 5 takes them off from the hurdle concerned and carries them out of the machine. The sheets then deliver the material supported by them to the conveying means 31, Fig. 2. It is advisable to guide the endless chain only once through the vertical transverse conveyers and to guide the return strand over guide rolls 34, 35 outside the range of the vertical conveying means.

The vertically guided hurdles may be delivered in pairs, as described, that is, there are always two hurdles lowered and raised, so that the hurdles of one conveyer travel upwardly when those of the other move down. As shown in Fig. 8, conveying may further be carried out by causing the descending portion of the vertical conveyers to deliver a hurdle to a band conveyer arranged below, after removal of the sheet this hurdle being instantly placed into charging position by the band conveyer, provided with a sheet and lifted. When the construction shown in Fig. 8 is employed, the two conveyers cannot simultaneously move up and down but only alternately.

To avoid the difficulties which arise when inside the cooling device a closed cycle of the hurdles is maintained, it is possible to construct the vertical conveyers in such manner that within them no circular course of the hurdles occurs which can then be fed to and removed from the cooling device while the rotating sheets of paper are placed on or withdrawn from the hurdles. Even in a device of this type it would be possible according to the invention to provide a single endless conveyer which guides the sheets in a cycle and delivers them to and removes them from the vertical conveyers.

I claim:

1. An apparatus of the class described comprising conveying means for continuously advancing sheets, a series of hurdles for receiving said sheets from said conveying means and returning the same thereto, means located above said conveying means for transporting said hur-

dles away from and toward said conveying means, a pair of tables located below said conveying means and adapted to pass through said conveying means, means for reciprocating said tables in opposite directions, means for receiving said hurdles before they have been passed by one of said tables through said conveying means from said means located above said conveying means and means for receiving said hurdles after they have been passed by the other table through said conveying means to said means located above said conveying means.

2. An apparatus of the class described comprising conveying means for continuously advancing sheets, a series of hurdles for receiving said sheets from said conveying means and returning the same thereto, endless means located above and at both sides of said conveying means for transporting said hurdles away from and toward said conveying means, a pair of tables located below said conveying means and adapted to pass through said conveying means, means for reciprocating said tables in opposite directions, means for receiving said hurdles before they have been passed by one of said tables through said conveying means from said means located above said conveying means, means for receiving said hurdles after they have been passed by the other table through said conveying means to said means located above said conveying means and means for transferring hurdles from one table to the other.

3. An apparatus of the class described comprising conveying means for continuously advancing sheets, a series of hurdles for receiving said sheets from said conveying means and returning the same thereto, a pair of endless means located above said conveying means and on each side thereof for transporting said hurdles away from said conveying means, a second pair of endless means located above said conveying means and on each side thereof for transporting said hurdles toward said conveying means, a table located below said conveying means and below each pair of endless means and adapted to pass through said conveying means, means for reciprocating said tables in opposite direction, means for transferring hurdles from one table to the other, means including pivoted levers for receiving said hurdles before they have been passed by one of said tables through said conveying means from one of said pairs of endless means to one of said tables and means for receiving said hurdles after they have been passed by the other table through said conveying means to the other pair of endless means.

4. An apparatus of the class described comprising conveying means for continuously advancing sheets, a series of hurdles for receiving said sheets from said conveying means and returning the same thereto, means located above said conveying means for transporting said hurdles away from and towards said conveying means, a pair of reciprocating tables located below said conveying means, means for transferring hurdles between said tables, a series of pivoted levers for supporting said hurdles so as to come within the field of action of said means located above said conveying means and means for operating said tables so as to bring the hurdles thereon within the field of action of said levers.

5. An apparatus of the class described comprising endless conveying means for continuously advancing sheets, a series of hurdles for

receiving said sheets from said conveying means and returning the same thereto, a pair of endless transporting means located above said conveying means and on each side thereof for transporting said hurdles after receiving a sheet from said conveying means away from said conveying means, a second pair of endless means located above said conveying means and on each side thereof for transporting said hurdles with a sheet thereon toward said conveying means, a 10 reciprocating table located below said conveying means and below each pair of endless means and adapted to pass through said conveying means, a series of pivoted levers for receiving said hurdles before and after they have been 15 passed through said conveying means by said tables and means for operating said levers and tables in proper timed sequence.

6. An apparatus of the class described comprising an endless conveying means for continuously advancing sheets along a horizontal path, a series of hurdles for receiving said sheets from said conveying means and returning the same thereto, a pair of endless conveyers located above said conveying means and on each side thereof for transporting said hurdles away from said conveying means, a second pair of endless means located above said conveying means and on each side thereof for transporting hurdles toward said conveying means, means located above said pairs of endless means for transferring hurdles from one pair of endless means to the other, a table located below said conveying means and below each pair of endless means, means for reciprocating said tables in opposite directions, means located on each side of said conveying means for receiving hurdles before and after they have been passed by said tables through said conveying means into the field of action of said pairs of endless means, said receiving means operating immediately above said conveying means and immediately below said conveying means and means for reciprocating said tables and said receiving means in timed sequence.

7. An apparatus of the class described comprising a pair of endless spaced synchronously intermittently operated chains having the upper runs thereof disposed substantially in a horizontal plane, oppositely mounted feeding means on said chains, carrier sheets, cross bars on said carrier sheets cooperating with said feeding means, hurdles having a width less than the spacing of said chains cooperating with said sheets, means for intermittently moving said hurdles upwardly from a point below the upper runs 55 of said chains between said chains to a point

above the upper runs of said chains, means for intermittently moving said hurdles downwardly in opposite direction, said hurdles being transferred upwardly and downwardly above said conveying means, said upward and downward movement of said hurdles taking place at spaced points along said upper runs and the intermittent movements of said hurdles being timed to take place while said chains are stopped.

8. An apparatus of the class described comprising a pair of endless spaced synchronously intermittently operated chains having the upper runs thereof disposed substantially in a horizontal plane, oppositely mounted lugs on said chains, carrier sheets, means on said sheets cooperating with said lugs, hurdles having a width less than the spacing of said chains cooperating with said sheets, means for intermittently moving said hurdles upwardly from a point below 20 said upper runs of said chains between said chains to a point above the upper runs of said chains, means for intermittently moving said hurdles downwardly in opposite direction said hurdles being transferred upwardly and downwardly above said conveying means, said upward and downward movement of said hurdles taking place at spaced points along said upper runs and the intermittent movements of said hurdles being timed to take place while said chains are stopped.

9. An apparatus of the class described comprising a pair of endless spaced synchronously intermittently operated chains having the upper runs thereof disposed substantially in a horizontal plane, oppositely mounted feeding means on said chains, carrier sheets, cross bars on said carrier sheets cooperating with said feeding means, hurdles having a width less than the spacing of said chains cooperating with said sheets, means for intermittently moving said hurdles upwardly from a point below the upper runs of said chains between said chains to a point above the upper runs of said chains, means for intermittently moving said hurdles downwardly in opposite direction, said hurdles being transferred upwardly and downwardly above said conveying means, said upward and downward movement of said hurdles taking place at spaced points along said upper runs and the intermittent movements of said hurdles being timed to take place while said chains are stopped and means for aligning said hurdles during their movement with said upper runs to receive said sheets therefrom and return said sheets thereto.

FRITZ NESTMANN.
